CLAIM

The ornamental design for a die with Hebrew letters, as shown and described.

DESCRIPTION

FIG. 1 is an elevational perspective view of the first embodiment of the new Hebrew die;

FIG. 2 is a side elevational view of a top side thereof, bearing the Hebrew letter Hei, shown broken away for ease of illustration;

FIG. 3 is a side elevational view of another top side thereof, bearing the Hebrew letter Gimel, shown broken away for ease of illustration;

FIG. 4 is a side elevational view of yet another top side thereof, bearing the Hebrew letter Nun, shown broken away for ease of illustration;

FIG. 5 is a side elevational view of still another top side thereof, bearing the Hebrew letter Shin, shown broken away for ease of illustration;

FIG. 6 is a side elevational view of a bottom side thereof, bearing the Hebrew letter Shin, shown broken away for ease of illustration;

FIG. 7 is a side elevational view of another bottom side thereof, bearing the Hebrew letter Nun, shown broken away for ease of illustration;

FIG. 8 is a side elevational view of yet another bottom side thereof, bearing the Hebrew letter Hei, shown broken away for ease of illustration;

FIG. 9 is a side elevational view of still another bottom side thereof, bearing the Hebrew letter Gimel, shown broken away for ease of illustration;

FIG. 10 is an elevational perspective view of the second embodiment of the new Hebrew die;

FIG. 11 is a side elevational view of a top side thereof, bearing the Hebrew letter Hei, shown broken away for ease of illustration;

FIG. 12 is a side elevational view of another top side thereof, bearing the Hebrew letter Gimel, shown broken away for ease of illustration;

FIG. 13 is a side elevational view of yet another top side thereof, bearing the Hebrew letter Pei, shown broken away for ease of illustration;

FIG. 14 is a side elevational view of still another top side thereof, bearing the Hebrew letter Nun, shown broken away for ease of illustration;

(Continued)

FIG. 15 is a side elevational view of a bottom side thereof, bearing the Hebrew letter Pei, shown broken away for ease of illustration;

FIG. 16 is a side elevational view of another bottom side thereof, bearing the Hebrew letter Nun, shown broken away for ease of illustration;

FIG. 17 is a side elevational view of yet another bottom side thereof, bearing the Hebrew letter Hei, shown broken away for ease of illustration; and,

FIG. 18 is a side elevational view of still another bottom side thereof, bearing the Hebrew letter Gimel, shown broken away for ease of illustration.
